CLAIM

We claim the ornamental design for a floating pool light, as shown and described.

DESCRIPTION

This article is intended to illuminate a body of water such as a swimming pool.

FIG. 1 is a perspective top quarter view of the pool light of the design.

FIG. 2 is a perspective bottom quarter view of the light of FIG. 1.

FIG. 3 is a front face view of the light of FIG. 1.

FIG. 4 is a bottom view of the light of FIG. 1.

FIG. 5 is a top view of the light of FIG. 1; and,

FIG. 6 is a side view of the light of FIG. 1.
